FIG 42

FIG. 1 is a side view of the shell for live bait, embodying a first form of the design.

FIG. 2 is a back view thereof.

FIG. 3 is a side view thereof, opposite from the side shown in FIG. 1.

FIG. 4 is a front view thereof.

FIG. 5 is a top view thereof.

FIG. 6 is a bottom view thereof.

FIG. 7 is a perspective view thereof.

FIG. 8 is a side view of the shell for live bait, embodying a second form of the design.

FIG. 9 is a back view thereof.

FIG. 10 is a side view thereof, opposite from the side shown in FIG. 1.

FIG. 11 is a front view thereof.

FIG. 12 is a top view thereof.

FIG. 13 is a bottom view thereof.

FIG. 14 is a perspective view thereof.

FIG. 15 is a side view of the shell for live bait, embodying a third form of the design.

FIG. 16 is a back view thereof.

FIG. 17 is a side view thereof, opposite from the side shown in FIG. 1.

FIG. 18 is a front view thereof.

FIG. 19 is a top view thereof.

FIG. 20 is a bottom view thereof.

FIG. 21 is a perspective view thereof.

FIG. 22 is a side view of the shell for live bait, embodying a fourth form of the design.

FIG. 23 is a back view thereof.

FIG. 24 is a side view thereof, opposite from the side shown in FIG. 1.

FIG. 25 is a front view thereof.

FIG. 26 is a top view thereof.

FIG. 27 is a bottom view thereof.

FIG. 28 is a perspective view thereof.

FIG. 29 is a side view of the shell for live bait, embodying a fifth form of the design.

FIG. 30 is a back view thereof.

FIG. 31 is a side view thereof, opposite from the side shown in FIG. 1.

FIG. 32 is a front view thereof.

FIG. 33 is a top view thereof.

FIG. 34 is a bottom view thereof.

FIG. 35 is a perspective view thereof.

FIG. 36 is a side view of the shell for live bait, embodying a sixth form of the design.

FIG. 37 is a back view thereof.

FIG. 38 is a side view thereof, opposite from the side shown in FIG. 1.

FIG. 39 is a front view thereof.

FIG. 40 is a top view thereof.

FIG. 41 is a bottom view thereof.

FIG. 42 is a perspective view thereof.

The broken lines in the drawing figures form no part of the claimed design and are for illustrative purposes only.

I claim:

The ornamental design for a shell for live bait, as shown and described.
